UNITED STATES PATENT OFFICE

90,797

DESIGN FOR A BODY FOR A TOY WAGON

Charles C. Blackmore, Dayton, Ohio, assignor to The Dayton Toy & Specialty Company,
Dayton, Ohio, a corporation of Ohio

Application May 1, 1933. Serial No. 47,952

Term of patent 14 years

To all whom it may concern:

Be it known that I, CHARLES C. BLACKMORE, a citizen of the United States, residing at Dayton, in the county of Montgomery and State of Ohio, have invented a new, original, and ornamental Design for Bodies for Toy Wagons, of which the following is a specification, reference being had to the accompanying drawing forming a part thereof.

The figure in the drawing is a perspective view of a body for toy wagons, showing my new design.

I claim:

The ornamental design for a body for a toy wagon, as shown.

CHARLES C. BLACKMORE.
